RELEASING GRIP TRIP

Edmond E. Himel, Jr., New Orleans, La.

Application January 17, 1956, Serial No. 559,625

4 Claims. (Cl. 294—75)

This invention relates to a release device for a chain hoist.

The object of the invention is to provide a release device for a chain hoist which will facilitate the lifting, transporting, storage and other handling of various materials such as sugar cane, lumber or the like.

Another object of the invention is to provide a release device for a chain hoist which includes a novel mechanism for releasing the device so that there will be no danger of the workmen being hurt by the load.

A further object of the invention is to provide a releasing chain grip trip for use as a material handling device whereby the operator of the crane or similar device will be able to release the load of material at will.

Another object of the invention is to provide a release device for a chain hoist which includes a single spring which is positioned or located so as to maintain sufficient pressure on the dog and latch whereby a weak or defective spring can be changed without the necessity of destroying all of the riveted pins.

A further object of the invention is to provide a releasing grip trip mechanism which is extremely simple and inexpensive to manufacture.

Other objects and advantages will be apparent during the course of the following description.

In the accompanying drawings, forming a part of this application, and in which like numerals are used to designate like parts throughout the same.

Figure 1 is a side elevational view illustrating the device in use and mounted on a chain or sling.

Figure 2 is an elevational view of the device with parts broken away and in section.

Figure 3 is a fragmentary elevational view illustrating one of the side plates.

Figure 4 is a plan view of the mechanism shown in Figure 2, and with the chain removed.

Figure 5 is a sectional view taken on the line 5—5 of Figure 2.

Figure 6 is a view similar to Figure 5 but illustrating a modified clamp.

Figure 7 is a perspective view illustrating the latch.

Figure 8 is a sectional view illustrating a modified form of releasing device.

Figure 9 is a plan view of the device shown in Figure 8.

Figure 10 is a sectional view taken on the line 10—10 of Figure 8.

Figure 11 is a sectional view taken on the line 11—11 of Figure 8.

Figure 12 is a sectional view taken on the line 12—12 of Figure 8.

Figure 13 is a sectional view similar to Figure 10 but illustrating a modification.

Figure 14 is a sectional view taken on the line 14—14 of Figure 5.

Referring in detail to the drawings the numeral 10 designates a chain, Figure 1, which may have a ring 11 attached to an end thereof. A disc or stop 12 may be mounted on the chain 10, and the ring 11 can be con-

2

nected to a member that is to be used for lifting a load such as a load of sugar cane, lumber or the like.

The present invention is directed to an article gripping mechanism 14 which includes a pair of spaced parallel plates 15 which may be made of any suitable material such as metal.

With the present invention the operator of a crane or similar device can release the load of material at will. Heretofore such devices have required one or more additional men depending on the load being handled to release the load independently of the crane operator. These men stand by in a very hazardous position to release each grip trip singly, and loads that are released in the air require one man for each sling that are released simultaneously to prevent excessive breakage by overloading the remaining slings. By means of the present invention, the releasing dogs that trip the load can be readily actuated from a crane or derrick so that with the present invention, one, two or more chain slings can be released simultaneously by the operator of the crane, derrick, boom, or similar device so that it will not be necessary for an excessive load to be carried or borne by any one or more trips and also the hand trippers are eliminated. Also, the present invention will not hinder the operation of the manual release system now in use and the device can be made with a minimum amount of expense.

Extending between one end of the plates 15 is a first pin 16 which has a pulley or sheave 17 mounted thereon, and a portion of the chain 10 engages the sheave 17. Extending between the pair of plates 15 is a second pin 18 which has a dog 19 mounted thereon, and formed integral with the dog 19 is a thumb tab 20 and chain stop 21.

There is further provided a third pin 22, which extends between the plates 15, and a latch 23 is movably mounted on the pin 22. A latch 23 is provided with a cutout 24 that defines a pair of spaced apart fingers 25 for a purpose that is later to be described. A hook member 27 is movably mounted on a pin 26, and an end of the chain 10 is adapted to engage the hook member 27.

Extending outwardly from the latch 23 is a boss 28, and a coil spring 29 has one end connected to the boss 28, while the other end of the coil spring 29 is connected to a boss 30 on the dog 19.

Each of the plates 15 is provided with an upwardly extending portion 31, and each of the portions 31 is provided with a slot or cutout 32, Figure 3. A clamp 33 includes a loop 34 which has a pair of straight portions 35 extended therefrom, and the straight portions 35 terminate in criss-cross portions 36 which each terminate in straight sections 37. The straight sections 37 terminate in inwardly extending aligned arms 38, and the arms 38 project through the slot 32. A suitable material such as the cable 39, Figure 1, is adapted to be connected to the loop 34 of the clamp 33 whereby the clamp can be actuated from a suitable location such as the crane being used.

Referring to Figure 6 of the drawings there is shown a modified arrangement wherein there is provided a modified clamp which is indicated by the numeral 42, and the clamp 42 serves the same purpose as the previously described clamp 33. The clamp 42 includes a loop 43 which terminates in a pair of straight portions 44, and extending from each of the straight portions 44 is an offset section 45 which terminates in a straight section 46, and the sections 46 terminate in outwardly projecting arms 47. The ends of the arms 47 may be movably mounted in grooves or slots 41 in side plates 40, and the plates 40 serve the same purpose as the previously described plates 15. The arms 47 are adapted to engage

fingers 48 of the latch 49, and the latch 49 functions in the same manner as the previously described latch 23.

Referring to Figures 8 through 12 of the drawings, there is shown a modified form of the device which is indicated generally by the numeral 50. The device 50 includes a pair of spaced parallel plates 51, and a chain such as the chain 10 is adapted to engage a curved guide member 53, and the guide member 53 serves the same purpose as the previously described sheave 17. Extending between the pair of plates 51 is a pin 52 which has a pawl or dog 54 mounted thereon. A thumb tab 55 is provided for actuating the dog 54. Extending between the pair of plates 51 is a block 56, and a bolt 59 serves to secure the pair of spring members 57 and 58 to the block 56. A body member 61 is movably mounted on a pin 60 which extends between the pair of plates 51, and the body member 61 is provided with a cut out 62 as well as a cylindrical cam portion 63. A hook member 64 is provided with a lever portion 65 which extends into the cut out 62, and the hook member 64 is mounted on a pin 66. Projecting from the side plates 51 is a bracket 67, and portions of the bracket 67 are spaced from the top edges of the side wall so as to define slots or cut outs 68 for engagement by arms such as the arms 38 of the clamp 33. A brace or stop member 69 may extend between the plates 51 and may be secured thereto in any suitable manner, as for example, by welding.

Referring to Figure 13 of the drawings, there is shown a modified form of the device which is indicated generally by the numeral 70, and the device 70 includes a pair of spaced parallel side plates 71 which may each be provided with slots 72 for engagement by the arms 47 of a clamp such as the clamp 42.

From the foregoing, it is apparent that there has been provided a release device for a chain hoist which is especially suitable for use in hoisting or otherwise handling loads of material such as sugar cane or lumber. In use, chains such as the chains 10 may be wrapped or trained around a load of material being handled, and then the ring 11 can be connected to a suitable hoist or crane by means of a hook, or the like. The clamp, such as the clamp 33 can also be connected to the crane by means of a normally slack cable 39, and with the parts arranged as shown in Figure 2 the gripping mechanism 14 will lock the chain 10 in its proper position on the load. When it is desired to release the chain 10, it is only necessary to apply tension to the cable 39. Pivotal movement of the latch 23 will free the hook member 27 so that the hook member 27 can pivot to permit disengagement of the chain 10 therefrom. At the same time, the dog 19 can be disengaged from the chain 10. The spring 29 tends to maintain the parts in their normally locked position.

Instead of using the clamp 33 shown in Figures 1 through 5, the clamp 42 can be used. Thus, the clamp 42 includes the outwardly projecting arms 47 which are movably mounted in grooves 41, so that by pulling on the clamp 42 by means of the cable 39, the arms 47 will engage beneath the fingers 48 of the latch 49 to thereby release the chain.

Referring now to Figures 8 through 12 of the drawings there is shown a still further modification wherein the chain 10 is again adapted to be wrapped or trained around a load of material such as logs, sugar cane or the like and the clamp 33 may be actuated by a crane operator by means of a suitable cable connected thereto. To disengage or release the chain 10, it is only necessary to apply pressure on the clamp 33 by means of a cable such as the cable 39 and this will pivot the body member 61, since the arms 38 will engage the cam portion 63 of the body member 61 when tension is applied to the clamp 33. As the body member 61 pivots, the lever 65 will be free to pivot on the pin 66 so that that portion of the chain which engages the hook 64 can be disengaged. Furthermore, pressure can be applied manually

on the tab 55 to pivot the pawl 54 so that the pawl can also be disengaged from the chain 10. The spring members 57 and 58 tend to maintain the parts in the position shown in Figure 8.

Instead of using the clamp 33 for actuating the body member 61, a clamp such as the clamp 42 shown in Figure 13 can be used. The clamp 42 has its outwardly projecting arms 47 slidably mounted in slots 72 in the side plates 71 of the gripping device 70.

With the present invention, a sling can be made using the chain 10 as shown in Figure 1 and with the device 14 attached thereto so that bundles of various materials such as sugar cane can be readily moved as desired and such material can be handled safely and speedily.

In Figure 8, when the bundle is choked, the pawl 54 latches in the chain 10 and prevents loosening of the bundle even when the lifting load is relaxed. The thumb tab 55 can be used for retracting the pawl 54 to release the chain by striking the tab 55 with an iron bar, the hook 64 having been previously released by actuating the clamp 33. The link on the hook 64 falls clear of the hook when the body member 61 is moved by means of the clamp. The disc 12 acts as a stop ring to limit movement of the chain in the device.

The release device for a chain hoist of the present invention will quickly tighten the bundle and hold the load tightly and positively and the device is light in weight and strong and safe to use. The arms such as the arms 38 and the clamp 33 may have circular flanges 73 welded or otherwise secured thereto for limiting inward movement of the arms. The spring 29 serves to return the latch 23 and dog 19 to their proper position and also maintain the desired pressure thereon.

It is to be understood that the releasing mechanism of the present invention whereby the clamp is used to release the device, is highly advantageous since the device can be released without the necessity of having a person standing close by the assembly.

The link which is looped over the hook 27 is identified by the numeral 74, and as previously described, the dog 19 includes the thumb tab 20 and chain stop 21. The chain stop 21 of the dog 19 has the same width as the sheave 17. With the present invention, a single spring is suitably located so as to maintain sufficient pressure on the dog and latch whereby a weak or defective spring can be changed without the necessity of destroying all of the riveted pins.

The operation of the device is as follows: Two or more chains are placed across the bottom of a cart, railroad flat car or truck with the releasing device 14 hanging over one side and the balance of the chain 10 over the other side. The material is located on top of the chain 10 and when completed the end link 74 is looped over the hook 27 and the chain 10 is pulled hand taut with the sheave 17 and dog 19 preventing the chain from loosening and the contents from flying out while being transported.

At the load's final destination the derrick or other suitable lifting device swings down and the driver of the vehicle will hook the end ring 11 on to the spreader bar (a bar with evenly spaced hooks to accommodate the number of slings that may be used on each load), and pulls the quick acting clamp 33 from guide eyes on the spreader bar which acts as a guide for cable 34. The clamp 33 is squeezed by hand along the straight portions 35 which open the arms 38 and is arranged in engagement with the finger 25 which is a part of the latch 23 and along the cutout 32 of the side plates 31. This operation is repeated for each sling used.

The operator of the hoisting device raises the load to any desired location and by applying pressure with the cable 39 which in turn pulls the clamp 33 free of the grooves, and in so doing actuates the latch 23 which released the hook 27 to thereby pivot and disengage the link 74 so that the load falls free. The clamps 33 then

immediately pull free of the trips 14 and return to the guide eyes of the spreader bar and are in position for the next load.

The spring 29 is attached to the dog 19 and latch 23 by bosses which may either be cast as part of the dog and latch or inserted later and these bosses are indicated by the numerals 28 and 30. Pressure is maintained by spring 29 on the cutout section of the hook 27 and keeps constant pressure through the chain stop 21 of the dog 19 on the chain 10 which is free to tighten around the bundle but is prevented from loosening on the bundle by the dog 19.

The modified releasing mechanism shown in Figure 8 operates the same as the previously described device with the exception that the clamp 33 is inserted under the arm 67 and when the lifting operator actuates the releasing cable 39, the arms 38 of the clamp 33 move outward and engage the cam portion 63 with a rearward pressure to release the hook 64 so as to pivot and release the end of the chain and the load then falls free.

As shown in Figure 14, the plates may be provided with grooves 76 for receiving pins 75 and this pin and groove arrangement acts to limit the rotation of the dog 19 and latch 23 in either direction.

I claim:

1. A release device for a chain hoist having a lift chain, said device comprising frame members, a hook adapted to engage said chain pivoted to said frame member, said hook when released being adapted to swing about its pivot to chain-releasing position, a retractable latch engaging said hook to hold the same in load-carrying position, a guide secured to said frame member having a surface over which a portion of said chain passes after passing around a load, said surface being shaped to guide said chain as it passes thereover, a pivotally mounted pawl engageable with the chain on said surface, a coiled spring having one end connected to said pawl for holding the same in load carrying position and adapted to permit retraction of said pawl for tightening of said chain around the load and the other end connected to said latch for holding said latch and said hook in load carrying position and adapted to permit retraction of said latch for releasing said load, said hook, said pawl and said latch all being disposed in longitudinal alignment with respect to each other.

2. A release device for a chain hoist having a lift chain, said device comprising frame members, a hook adapted to engage said chain pivoted to said frame members, said hook when released being adapted to swing about its pivot to chain-releasing position, a guide secured to said frame members having a surface over which a portion of said chain passes after passing around a load, said surface being shaped to guide said chain as it passes thereover, a pivotally mounted pawl engageable with the said chain on said surface and adapted to be automatically retracted for the tightening of said chain around the load, a latch pivoted to said frame members and adapted to engage said hook to hold the same in load-carrying position, a coiled spring having one end connected to said latch and the other end thereof connected to said pawl for normally holding said latch in latching engagement with said hook and said pawl in engagement with said chain, a trip member insertable in said frame member in a position to engage said latch, said hook, said pawl and said latch all being disposed in longitudinal alignment with respect to each other, means including a trip cord connected to said trip member and adapted

to actuate the same, and guide means carried by said frame members to guide said trip member when so actuated in a path to engage and retract said latch.

3. A release device for a chain hoist having a lift chain, said device comprising frame members, a hook adapted to engage said chain pivoted to said frame members, said hook when released being adapted to swing about its pivot to chain-releasing position, a guide secured to said frame members having a surface over which a portion of said chain passes after passing around a load, said surface being shaped to guide said chain as it passes thereover, a pivotally mounted pawl engageable with the said chain on said surface and adapted to be automatically retracted for the tightening of said chain around the load, a latch pivoted to said frame members and adapted to engage said hook to hold the same in load-carrying position, a coiled spring having one end connected to said latch and the other end thereof connected to said pawl for normally holding said latch in latching engagement with said hook and said pawl in engagement with said chain, said hook, said pawl and said latch all being disposed in longitudinal alignment with respect to each other, said frame members having aligned slots disposed to guide a trip member in a path to engage and retract said latch and a trip member having a pair of spring arms extendable along the sides of said frame members and having inturned ends extending through said slots and engageable with said latch, and means including a trip cord connected to said trip member and adapted to actuate the same for retracting said latch and thereby releasing the load.

4. A release device for a chain hoist having a lift chain, said device comprising frame members, a hook adapted to engage said chain pivoted to said frame members, said hook when released being adapted to swing about its pivot to chain-releasing position, a guide secured to said frame members having a surface over which a portion of said chain passes after passing around a load, said surface being shaped to guide said chain as it passes thereover, a pivotally mounted pawl engageable with the said chain on said surface and adapted to be automatically retracted for the tightening of said chain around the load, a latch pivoted to said frame members and adapted to engage said hook to hold the same in load-carrying position, a coiled spring having one end connected to said latch and the other end thereof connected to said pawl for normally holding said latch in latching engagement with said hook and said pawl in engagement with said chain, said hook, said pawl and said latch all being disposed in longitudinal alignment with respect to each other, said latch having a bifurcated end portion forming a longitudinal slot, said frame members having aligned grooves disposed to guide a trip member in a path to engage and retract said latch and a trip member comprising a pair of spring arms having vertical portions extending through said slot and having horizontal end portions extending into said grooves and engageable with said latch, and means including a trip cord connected to said trip member and adapted to actuate the same for retracting said latch and thereby releasing the load.
